UNITED STATES PATENT OFFICE.

PAUL E. WIRT, OF BLOOMSBURG, PENNSYLVANIA.

DESIGN FOR A MASSAGING DEVICE.

SPECIFICATION forming part of Design No. 35,313, dated November 26, 1901.

Application filed October 19, 1901. Serial No. 79,305. Term of patent 14 years.

To all whom it may concern:

Be it known that I, PAUL E. WIRT, a citizen of the United States, residing at Bloomsburg, in the county of Columbia and State of Pennsylvania, have invented and produced a certain new and original Design for a Massaging Device, of which the following is a specification.

This invention relates to a new and original design for a massaging device; and it has for its object to provide a design of this character which shall be both useful and ornamental.

The leading or characteristic feature of the design resides in a skeleton rubbing member having a body and a plurality of working fingers connected at one end with the body and having free scalp-engaging ends beyond the latter, said fingers being inflexed and arranged in a transverse row in spaced relation.

Another distinctive feature of the design resides in the bunch or group of fingers as an entirety being arched at the massaging end fitting the head, as the working fingers are arranged transversely in an arcuate row.

The minor features of the design are the elongated handle, the laterally-expanded body or head sustaining the working fingers, and also the cylindrical form of the fingers. Other minor features are the outwardly-divergent relation of the fingers and the enlarged terminal contacts at the tips thereof.

In the drawing the figure is a perspective view of a massaging device embodying the herein-described design, the view showing the non-essential elongated handle in dotted lines and the part embodying the essential feature in full lines.

Referring particularly to the drawing, the numeral 1 designates an elongated support-

ing or manipulating handle of suitable form, and which is illustrated as carrying at one end thereof a laterally-expanded body or head 2, forming the base of what might be properly termed "skeleton rubbing member" 3 of the device. The said skeleton rubbing member 3 includes the body or head 2 and a plurality of working fingers 4, connected in transverse alinement at one end with the laterally-expanded body or head 2, said working fingers 4 having free scalp-engaging ends beyond their connection with the said body or head 2. In the embodiment of the invention disclosed in the drawing the working fingers 4 are illustrated as being of a cylindrical form and provided at their tips with massaging-contacts 5. With reference to the relation of the individual fingers 4 it is to be observed that they are similarly curved in an inward direction, or, in other words, are inflexed, besides being arranged in a transverse row in spaced relation. As shown, the bunch or group of working fingers as an entirety are arched at the massaging end, fitting the head, inasmuch as the fingers are arranged transversely in an arcuate row at their tips.

Another feature of the design which is shown is that of the series of working fingers being disposed in an outwardly-divergent relation.

What I claim is—

The design for a massaging device herein shown and described.

In testimony whereof I affix my signature in presence of two witnesses.

PAUL E. WIRT.
